CLAIM

The ornamental design for a pyranometer, as shown and described.

DESCRIPTION

FIG. 1 is a perspective view of a pyranometer showing our new design;

FIG. 2 is a front view thereof;

FIG. 3 is a rear view thereof;

FIG. 4 is a top view thereof;

FIG. 5 is a bottom thereof;

FIG. 6 is a right side view thereof; and,

FIG. 7 is a left side view thereof.

The broken line disclosure does not form part of the claimed design.
